LAVATORY

Donald C. Schrock, Nevada, Mo., assignor to
Crane Co., New York, N.Y.

Filed Apr. 16, 1973, Ser. No. 351,707

Term of patent 14 years

Int. Cl. D23—02

U.S. Cl. D23—58

Fig. 1.

Fig. 1.

Fig. 2.

Fig. 3.

FIG. 4.

FIG. 5.

FIG. 6.

FIG. 1 is a top plan view of a lavatory showing my new design;

FIG. 2 is a front elevational view thereof;

FIG. 3 is a sectional view taken along line 3—3 of FIG. 1;

FIG. 4 is a top plan view similar to FIG. 1 wherein the lavatory is slightly tilted along its front edge to thereby expose the integral, recessed soap dish;

FIG. 5 is a rear elevational view thereof; and

FIG. 6 is a side elevational view looking from the left of FIG. 1.

I claim:

The ornamental design for a lavatory, as shown.
